DESIGN FOR A FLOOR COVERING

Charles O. Karpf, New York, N. Y., assignor to Mannington Mills, Incorporated, Salem, N. J.,
a corporation of New Jersey

Application November 21, 1933. Serial No. 49,816

Term of patent 7 years

To all whom it may concern:

Be it known that I, CHARLES O. KARPF, a citizen of the United States and a resident of New York city, State of New York, have invented a new, original, and ornamental Design for a Floor Covering, of which the following is a specification reference being had to the accompanying drawing, forming part thereof, in which the figure is a face view illustrating my new design for a floor covering.

I claim:—

The ornamental design for a floor covering, substantially as shown.

CHARLES O. KARPF.
